(57) **CLAIM**

The ornamental design for a truck chassis rear fairing, as shown and described.

DESCRIPTION

FIG. 1 is a front perspective view of a truck rear chassis fairing showing our new design;

FIG. 2 is a right side elevational view of the truck chassis rear fairing of FIG. 1;

FIG. 3 is a top plan view of the truck chassis rear fairing of FIG. 1;

FIG. 4 is a bottom plan view of the truck chassis rear fairing of FIG. 1;

FIG. 5 is a front elevational view of the truck chassis rear fairing of FIG. 1;

FIG. 6 is a rear elevational view of the truck chassis rear fairing of FIG. 1; and,

FIG. 7 is a front perspective view of the truck chassis rear fairing of FIG. 1 and an environment related to the truck chassis rear fairing of our new design.

The broken lines in the drawing form no part of the claimed design.

FIGS. 1-7 illustrate a first embodiment of our novel design suitable for use on the right side of a truck. Our novel design also includes a second embodiment suitable for use on the left side of a truck, which is mirror symmetrical to FIGS. 1-7, and therefore not separately illustrated.

1 Claim, 6 Drawing Sheets
